UNITED STATES PATENT OFFICE

165,920

PAINT-MIXING MACHINE

William E. Holt, Oakland, Calif.

Application April 16, 1951, Serial No. 14,857

Term of patent 14 years

(Cl. D55—1)

To all whom it may concern:

Be it known, that I, William E. Holt, a citizen of the United States, residing at Oakland, in the county of Alameda and State of California, have invented a new, original, and ornamental Design for Paint-Mixing Machine, of which the following is a specification, reference being had to the accompanying drawing, forming part thereof.

Fig. 1 is a perspective view of a paint-mixing machine, showing my new design, with the can clamping means in position for holding a can; the side of the machine not shown being substantially like the machine side shown; and

Fig. 2 is an end view of the machine shown in Fig. 1.

I claim:

The ornamental design for a paint-mixing machine, as shown and described.

WILLIAM E. HOLT.
